UNITED STATES PATENT OFFICE.

VARNUM D. COLLINS, OF PRINCETON, NEW JERSEY.

MOSQUITO OR FLY NET.

SPECIFICATION forming part of Letters Patent No. 474,947, dated May 17, 1892.

Application filed January 7, 1892. Serial No. 417,303. (No model.)

To all whom it may concern:

Be it known that I, VARNUM D. COLLINS, a citizen of the United States of America, residing at Princeton, in the county of Mercer 5 and State of New Jersey, have invented certain new and useful Improvements in Mosquito or Fly Nets, of which the following is a specification, reference being had therein to the accompanying drawings.

10 It is the object of my invention to provide a canopy for the protection of the head, face, and upper portion of the body against the attacks of mosquitoes and other insects, the invention being intended for use particularly 15 while the person is reclining or lying down. In providing this improved canopy I aim to render it capable of folding into a small compass while not in use, to make it portable, and of such simple construction as will enable it 20 to be manufactured at small expense.

The invention consists of a canopy comprising a suitable netting and a supporting-frame therefor, consisting of three bow-shaped wires, the ends of which are pivotally connected together, two of the bows being arranged to form the base of the frame when unfolded by assuming a horizontal position, while the third bow extends from side to side of the base-frame thus formed in a curve to 25 30 keep the central portion of the netting elevated.

The invention includes, also, the special means by which the several bows of the frame are locked in unfolded position, and also the 35 means by which the unfolding action is limited.

In the accompanying drawings, Figure 1 represents a perspective view of the canopy in its unfolded position. Fig. 2 represents 40 the frame as folded, and Fig. 3 is a plan view of the locking device.

In the drawings it will be seen that the canopy-frame is made up of three bow-shaped wires or rods 1, 2, and 3. While I prefer to 45 use this number of bows as being amply sufficient, it will be understood that the features of my invention might be embodied in a frame having a larger number of wires. It is essential, however, to the full attainment 50 of the desired result, that the two wires 1 and 3 be arranged to lie in a horizontal plane

when spread out, as shown in the figures, and when in this position the intermediate bow 2 will curve over the base thus formed, it being held by a band or cord 4, attached to 55 the bows of the base-frame. The netting is stretched over the frame, and is secured in any suitable way to the wires of the base-frame 1 3. The covering is continued below the base, either in the form of netting or 60 fringe, as shown at 5. From this construction it will be seen that the canopy is well adapted to be placed over the face of a reclining or sleeping person, the horizontal base-frame enabling it to be supported firmly and 65 closely against the bedclothing and the body of the sleeper, while the depending fringe or netting adapts itself to any inequalities in the surface, and effectually closes all spaces through which the insects might enter the 70 interior of the canopy. At the same time the netting of the canopy is held properly elevated and away from the face of the sleeper by the central bow 2. The hinged connection between the bows is formed by the interlocking hooks or eyes at the ends thereof, as shown at 6, this providing a simple and 75 inexpensive form of connection. In order to limit the spreading action of the bows, an extension is formed on one of the ends of the 80 horizontal bow 3, and this is bent, as at 7, to provide a bearing for the under side of the other horizontal bow, which when opened 85 strikes thereagainst and is prevented from moving farther. In addition to this a limiting or locking extension 8 is formed on the other side of the base at the other joint, and this is of such length as to give slight flexibility, so that it can be pressed aside to allow 90 its end to spring over the upper side of the bow 1, and thus prevent closing movement of the bows. The central bow is held firmly by the band or cord attached thereto and to the base bows.

When the canopy is folded, the bows lie side 95 by side. The frame is preferably made of wire in order to secure strength and lightness.

I claim as my invention—

A canopy-frame consisting of three bows pivoted by their interlocking ends, two of 100 which are horizontal and the other vertical, the wire of one of the horizontal bows being

extended at the joint on one side below the other horizontal bow to limit the outward movement of the opposite outer bows and having also the spring extension at the other joint to be pressed over the other horizontal bow to retain the two outer bows in open horizontal position, and the flexible connection from the outer bows to the central vertical bow for holding it centrally and vertically

over the horizontal bows, substantially as described.

In testimony whereof I affix my signature in presence of two witnesses.

VARNUM D. COLLINS.
